UNITED STATES PATENT OFFICE.

KATHARINE JANE HOOKER, OF GENESEO, NEW YORK.

TRAYS FOR INCUBATORS.

1,116,704.

Specification of Letters Patent. Patented Nov. 10, 1914.

Application filed May 28, 1913. Serial No. 770,467.

To all whom it may concern:

Be it known that I, KATHARINE JANE HOOKER, a citizen of the United States, residing at Geneseo, in the county of Livingston, State of New York, have invented certain new and useful Improvements in Trays for Incubators; and I do hereby declare the following to be a full, clear, and exact description of the invention, such as will enable others skilled in the art to which it appertains to make and use the same.

The present invention is directed to improvements in trays for incubators, and has for its object to construct trays for this purpose formed in sections so that the same can be handled separately when in use in an incubator of large proportions.

A further object of the invention is to provide trays having means for connecting the same so that when one tray is removed the other will be positioned for convenient removal.

It is a well known fact that in incubators employing trays which are adapted to contain in the neighborhood of four hundred eggs that it is quite a hardship to handle and remove the long trays, and it is to overcome this objection that the present invention is constructed.

With these and other objects in view, this invention resides in the novel features of construction, formation, combination and arrangement of parts to be hereinafter more fully described, claimed and illustrated in the accompanying drawings, in which:—

Figure 1 is a perspective view of an incubator. Fig. 2 is a sectional view on line 2—2 of Fig. 1, showing the position of the innermost tray upon the removal of the outermost tray. Fig. 3 is a similar view showing the trays in the position previous to the removal of the outermost tray. Fig. 4 is a detail sectional view of the means for locking the trays together.

Referring to the drawing, the numeral 1 designates an incubator of any well known construction, and 2 the incubator chambers, and in which the trays 3 are placed when the incubator is in operation. The trays 3 may be of any conventional form, and are adapted for removable engagement in the

incubation chamber 2. One of the trays 3 has one of its side walls provided with a loop 4, while the other tray has its similar wall provided with a spring catch 5, which is adapted to automatically engage the loop 4 to connect the trays. The spring catch 5 may be of any well known construction, or if desired any other form of catch may be substituted therefor.

From this construction it will be seen that when it is desired to remove the trays from the incubation chamber to change the eggs it is only necessary to pull the outermost tray outwardly, which action will cause the innermost tray to move forwardly to the forward or open end of the chamber, after which the outermost tray is disengaged from the innermost tray upon manipulation of the catch 5. The outermost tray is then placed upon a suitable table or support and the eggs turned, and as the innermost tray has been brought forwardly it is in convenient reach of the operator for removal. After the eggs have been turned one of the trays is placed in the forward part of the chamber 2, and the other tray is placed thereagainst, so that upon moving the tray which occupies the outermost position inwardly, the other tray will be forced to its proper position in the chamber 2, and during which time the pressure necessary to force the outermost tray forwardly will cause the automatic engagement of the catch 5 and loop 4, or if another form of catch is used, it may be manipulated by the operator.

From the foregoing description it will be seen that egg trays for incubators have been provided which are so constructed that the same will be connected when being placed in the incubation chamber of the incubator, and that upon removal of one tray will cause the other tray to assume a position for ready removal, thus eliminating the necessity of the operator reaching back into the incubator chamber to remove the normally innermost tray.

What is claimed is:—

In an incubator, the combination with the incubation chamber, of a pair of trays removably mounted in said chamber, a loop

carried by the side of one tray and a catch carried by one side of the other tray to automatically engage the loop to lock said trays together whereby when one tray is moved outwardly the other tray will be moved forwardly in said chamber, as and for the purpose set forth.

In testimony whereof I affix my signature in the presence of two witnesses.

KATHARINE JANE HOOKER.
